(57) **CLAIM**

The ornamental design for a combined package with locking mechanisms, as shown and described.

DESCRIPTION

FIG. 1 is a top, front, right-side perspective view of a combined package with locking mechanisms, in a closed configuration, showing the new design;

FIG. 2 is a top, front, left-side perspective view of the combined package with locking mechanisms, in the closed configuration;

FIG. 3 is a bottom, back, left-side perspective view of the combined package with locking mechanisms in a closed configuration;

FIG. 4 is a bottom, back, right-side perspective view of the combined package with locking mechanisms, in the closed configuration;

FIG. 5 is a bottom, right-side perspective view of the combined package with locking mechanisms, in the closed configuration;

FIG. 6 is a bottom, left-side perspective view of the combined package with locking mechanisms, in the closed configuration;

FIG. 7 is a front elevation view of the combined package with locking mechanisms, in the closed configuration;

FIG. 8 is a back elevation view of the combined package with locking mechanisms, in the closed configuration;

FIG. 9 is a right-side elevation view of the combined package with locking mechanisms, in the closed configuration;

FIG. 10 is a left-side elevation view of the combined package with locking mechanisms, in the closed configuration;

FIG. 11 is a top view of the combined package with locking mechanisms, in the closed configuration;

FIG. 12 is a bottom view of the combined package with locking mechanisms, in the closed configuration;

(Continued)

FIG. 53 is a front elevation view of the combined package with locking mechanisms, with the primary lid and the secondary lid in the respective opened configurations; FIG. 54 is a back elevation view of the combined package with locking mechanisms, with the primary lid and the secondary lid in the respective opened configurations; FIG. 55 is a right-side elevation view of the combined package with locking mechanisms, with the primary lid and the secondary lid in the respective opened configurations; FIG. 56 is a left-side elevation view of the combined package with locking mechanisms, with the primary lid and the secondary lid in the respective opened configurations; FIG. 57 is a top view of the combined package with locking mechanisms, with the primary lid and the secondary lid in the respective opened configurations; and, FIG. 58 is a bottom view of the combined package with locking mechanisms, with the primary lid and the secondary lid in the respective opened configurations.
